UNITED STATES PATENT OFFICE.

CHARLES B. FAIRWEATHER, OF COATESVILLE, PENNSYLVANIA, ASSIGNOR
TO J. S. WORTH AND W. P. WORTH, OF COATESVILLE, PENNSYLVANIA.

COVER-PLATE FOR BOILERS.

SPECIFICATION forming part of Letters Patent No. 722,571, dated March 10, 1903.

Application filed November 30, 1901. Serial No. 84,226. (No model.)

To all whom it may concern:

Be it known that I, CHARLES B. FAIRWEATHER, a citizen of the United States, and a resident of Coatesville, Pennsylvania, have 5 invented certain Improvements in Cover-Plates for Boilers, &c., of which the following is a specification.

The object of my invention is to make a man-hole cover-plate for boilers, &c., of a single 10 piece of sheet-steel or other metal struck up into form, and to which can be rigidly secured the bolts by which it is attached to the yokes. 15 This object I attain in the following manner, reference being had to the accompanying drawings, in which—

Figure 1 is a perspective view of my improved manhole cover-plate for boilers, &c. Fig. 2 is a front view. Fig. 3 is a rear view. Fig. 4 is a longitudinal sectional view. Fig. 20 5 is a transverse sectional view on the line 5 5, Fig. 4. Fig. 6 is a transverse sectional view on the line 6 6, Fig. 4.

A is the shell of the boiler, having an oblong opening surrounded by an internal flange a'. 25 B is the cover-plate for closing the opening. This cover-plate has an annular flange b, which bears against the flange a' of the boiler-plate A, and mounted between the two flanges a' and b is any suitable packing c. 30 The cover-plate B is made, preferably, of a single sheet of steel struck up to the form shown clearly in the drawings.

b' is the central portion of the cover-plate having flat or plain surfaces d d, which are 35 perforated at e e for the passage of the bolts D D. These bolts have heads d' and are screw-threaded and provided with nuts d², which are screwed down tightly onto the cover-plate and hold the bolts D rigidly to the 40 plate. I provide any suitable packing c' between the heads d' of the bolts and the cover-plate, so as to make a tight joint.

The metal of the cover-plate is shaped to 45 form an annular hollow rib b² at the front and a recess b³ at the back between the central portion b' of the cover-plate and the flange, thus not only strengthening the cover-plate considerably, but also forming a guide for the adjustment of the cover-plate to the manhole- 50 opening.

The two plain surfaces d d of the cover-plate are separated by a hollow curved rib f, which extends from one side to the other and stiffens the center portion of the plate.

G G are two yokes, in the present instance 55 of the usual form, which rest upon the boiler-shell and through which passes the bolts D D. Nuts d³ on the bolts are for the purpose of drawing the cover-plate tightly to its seat against the flange a' of the boiler-shell, making 60 a very rigid cover-plate with a tight joint between the cover-plate and the boiler-shell.

I claim as my invention—

1. The combination in a cover-plate for boilers, of the body portion having an annular 65 flange and a center portion with an annular hollow rib between the center portion and the flange, two flat surfaces on the center portion separated by a rib, and perforations in the flat surfaces of the cover-plate, with bolts having 70 removable means whereby they are rigidly secured to the flat portions of the cover-plate, substantially as described.

2. The combination of a cover-plate for boilers, a sheet-steel plate struck up from a 75 single sheet of metal and having an annular flange, an annular hollow rib, and a center portion having perforated flat surfaces separated by a central rib, headed bolts extending through the perforations, nuts on the bolts by 80 which the bolts are confined to the head, and packing between the heads of the bolts and the cover-plate, substantially as described.

3. As a new article of manufacture, a cover-plate for boilers, made of a single sheet of 85 metal struck up into form and having a central portion, with two substantially plane surfaces separated by a rib, an annular flange, and a hollow rib between the center and the flange, substantially as described. 90

In testimony whereof I have signed my name to this specification in the presence of two subscribing witnesses.

CHARLES B. FAIRWEATHER.
